US00D620228S

(12) **United States Design Patent**
Jones et al.

(10) **Patent No.:** US D620,228 S
(45) **Date of Patent:** ** Jul. 27, 2010

(54) **SINGLET**

(75) Inventors: **Gavin Jones**, Darlinghurst (AU); **Corie Chung**, Paddington (AU)

(73) Assignee: **Equmen Pty Ltd** (AU)

(**) Term: **14 Years**

(21) Appl. No.: **29/333,760**

(22) Filed: **Mar. 13, 2009**

(30) **Foreign Application Priority Data**

Sep. 15, 2008 (AU) 14403/2008

(51) **LOC (9) Cl.** 02-02

(52) **U.S. Cl.** D2/717

(58) **Field of Classification Search** D2/717,
D2/731, 741, 840, 841, 844; 2/90, 106, 113,
2/115

See application file for complete search history.
